RADIATOR STRUCTURE

Clifford J. Schlafman, Merchantville, N. J., assignor to Warren Webster & Company, Camden, N. J., a corporation of New Jersey

Application July 17, 1935, Serial No. 31,825

8 Claims. (Cl. 237—73)

This invention relates to radiator structures, and has particular reference to steam heating systems utilizing concealed radiation such as employed to heat dwellings, offices, and the like.

The invention further relates to radiator structures of the concealed convector type incorporating improved valves and thermostatic traps which provide flexibility in connection to the supply and return pipes and which provide adjustable means adapted for plumbing and supporting the heating element.

During the construction of dwellings and other buildings, steam supply pipes and return pipes are roughed-in prefatory to connection of radiators, when the heating system installation work is being done in the building, and, in practice, it is frequently found that unless particular attention has been paid to the location of such pipes to the radiator manufacturers' specification, the pipes do not accurately align with the radiator piping connections and thus serious difficulties are encountered when the radiators are being set in position.

Misalignment in piping is most troublesome in installations using straightway pattern traps and valves, which are generally employed at the present time, for convector type radiators. Also, in buildings having concrete floors, it is necessary to install sleeves at time of pouring of floors to provide passageways for stub-up pipe pieces but even though these may be accurately located preliminary to pouring of floor they are most frequently found out of line after concrete forms are removed because of the rough character of the work involved with its attendant shifting of sleeves, the dispatch with which pouring is executed and the lack of coordination between various sub-contractors and tradesmen. In the circumstances, the steamfitter, at extra expense and labor, must chip out openings in the concrete which will permit centering stub-up pipe pieces accurately. Again, because of architectural motif, radiators are usually centered beneath window openings. This fixes location of radiator piping connections. Occasionally, however, structural floor beams conflict with stub-up pipe pieces making it necessary to resort to special and costly arrangements, such as elevating radiator above floor to permit offsetting piping above beam, etc.

The present invention has for its primary object the construction of a radiator structure incorporating a trap and valve which permit preliminary roughing-in of piping without regard for accuracy in the location of stub-up pipe

pieces, or which permit substantially selective positioning of stub-up pipe pieces without regard for radiator dimensions.

Another object of the invention is to provide a radiator structure comprising a sheet metal enclosure, a heating element, a valve, and thermostatic trap so constructed as to simplify piping connections.

A still further object of the invention is to provide such a radiator structure in which means are provided on the valve and trap to support and grade the radiator for proper pitch and drainage of condensate.

A still further object of the invention is to provide a radiator structure comprising a sheet metal enclosure, a heating element, a valve and trap so constructed that stresses, normally imposed on heating element and/or enclosure, due to inherent weight of piping or set-up because of expansion or contraction of piping due to temperature changes, are absorbed through valve and trap supporting members.

A still further object of the invention is to provide an improved valve and thermostatic trap for use with concealed convector type radiators.

According to the invention, the radiator structure comprises an enclosure, a heating element, a steam supply valve, and a thermostatic trap, the inlets of said valve and trap being at substantially right angles to their outlets, said inlet and outlet connections provided with ball-jointed means for flexibility in connection and adjustable feet on said valve and trap to plumb and support the heating element.

The drawings illustrate an embodiment of the invention and the views therein are as follows:

Fig. 1 is a front elevation of the radiator structure connected with the supply and return pipes, and one-half of said view shows the use of a baseboard at the base of the radiator while the other side shows the use of a metallic grille,

Fig. 2 is a vertical sectional view taken on the line 2—2 of Fig. 1,

Fig. 3 is a vertical sectional view of the thermostatic trap with parts thereof shown in elevation,

Fig. 4 is an end view of the same,

Fig. 5 is a top plan view thereof,

Fig. 6 is a vertical sectional view of the steam valve with a part thereof in elevation, and shows the operating handle connected with the valve stem,

Fig. 7 is a side view of the same with the valve stem shown in section,

Fig. 8 is a top and plan view thereof.

Fig. 9 is an enlarged detail vertical sectional view of the inlet to the trap shown in Figure 3.

While the present invention shows a radiator installed within a plaster-surfaced wall, it will be understood that the invention relates not only to this type of installation but may be employed with a radiator installed within a wall recess and covered completely with a metal panel, or the structure may be housed within a cabinet where it is impracticable to place the same within in the wall.

In the structure shown, the heating element 12 comprises the pipes or tubes 13 connecting the headers 14 at each end of the same. The heating tubes are provided with metallic fins 16 extending continuously between baffles 17 which guide the flow of air through said fins, thereby assuring the heating of all air.

The heating element is located preferably within the chamber 18 and the opening in the upper end of the chamber is provided with a grille 19 while the opening at the bottom of said chamber is provided with a grille 21 or with a base-board 22 having an arched inlet opening as shown at 23, as preferred.

The bottom of each of the headers has a pipe tapped hole 24 for connection with the supply valve 26 at one side and with the thermostatic trap 27 at the other side.

In the setting of stub-up pieces for connection with the valve and trap, it has heretofore been the practice to endeavor to align the same with the pipe threaded openings 24 in the headers, but due to many inaccuracies in the location of these stub-up pieces serious difficulties were encountered when connection was to be made with the straightway trap, valve and radiator.

In the present invention, the enclosure with heating element comprising the tubes 13, headers 14 and baffles 17 is conventional and no claims are made to any invention in connection with this element per se.

The improved thermostatic trap is shown in Figs. 3, 4 and 5, and comprises a body 28 having an inner wall 29 dividing the interior of said body into chambers 31 and 32. This wall has an opening 33 provided with a seat 34 for a needle valve 36 which said needle valve is controlled by a thermostatic element 37.

The upper end of the body is provided with a tubular portion 38 having a convex end 39 terminating in a screw threaded portion 41 while a connecting nipple member 42, having a pipe threaded end 43 and an inner inclined-faced flange 44, cooperates with the convex end 39 of the tubular part 38 of said body, and said parts are adjusted and clamped into position by means of the union nut 46 as shown in Fig. 3. The connecting member has internal lugs 45 whereby a 60 spud wrench may be inserted for screwing the said member into the pipe threaded opening 24 in the header 14.

The bottom of said body is likewise provided with a horizontal extending circular part 47 which has its end formed in exactly the same manner as the circular part 38 and is provided with a female nipple connection 48 providing with the union nut 49 a ball-joint having the same structure as that just previously described.

The bottom of the body 28 is also provided with lateral extending lugs 51 provided with tapped holes 52 for receiving screw threaded feet 53 which said feet have heads 54 providing means for adjusting the said feet with respect to said lugs.

The valve shown in Figs. 6, 7 and 8 comprises a body 56 having a ball connection 57 at its upper end, precisely the same as the ball connection at the upper end of the tubular portion 38 of the trap shown in Fig. 3. This valve is provided with an upper chamber 58 and lower chamber 59, with a port 61 between the same, and controlled by the valve structure 62. This valve structure is operated by means of the valve stem 63 which is jointed at 64 and the parts are normally held together by means of a U-shaped spring 66 while an operating knob 67 is connected to the end of said valve stem by means of an internal friction spring 68, so that said knob, or handle, may be removed from the end 15 of the valve stem for mounting the valve in position.

The lower chamber 59 has two oppositely positioned fluid inlets 69 and 71, arranged so that piping connections may be made from either side of the valve. This valve is provided with a male and female ball-joint union connection 72 for operatively connecting the valve to a steam supply pipe. The bottom of the valve is also provided with lateral lugs 75 having screw threaded openings 76 for the adjustable mounting of screw threaded feet 77 which are the same as the feet 53 used on the trap shown in Figs. 3, 4 and 5.

Referring now to Fig. 1, the stub-up pieces A and B represent respectively the supply and return pipes. These pipes, in practice, are cut down to their proper heights and threaded. An elbow 73 is screwed on to the end of each of said pipes and nipples 74, cut to suitable length as necessary, are screwed into said elbows and into the female ends 72a and 48 respectively of the valve and trap union nipples.

In Fig. 1, the steam supply pipe A being nearest the right end of the radiator, this type is known as a "right hand supply". In practice, steam supply pipes may be either right or left hand, depending upon preference or circumstance.

It will be seen that if the steam supply pipe A were at the left hand end of the structure of Fig. 1, the trap could be conveniently placed and without change to the right; but on account of the valve stem 63, in order to connect the said valve at the left hand of the radiator, it would be necessary to remove the male and female union connection 72 from the outlet in which it is shown in Fig. 1, viz. 69, and thread it into the opening 71.

Of course, it will be understood that the unused opening 69 or 71 will be closed by a plug 80 (see Fig. 2).

When heating systems are being installed, the steamfitter "roughs-in" the piping first, that is, all piping is completed except that the radiators are not set nor connections made thereto through the valves and traps. However, the stub-up pieces A and B are installed and these are usually capped to prevent entry of dirt previous to setting and connecting up the radiator structures.

With the type of radiator structure herein disclosed, no regard need be taken for the location of these stub-up pipe pieces A and B except approximate, which greatly simplifies "roughing-in" work or location of stub-up pipe pieces can be selected, if preferred, without regard for radiator dimensions.

When the contractor is ready to install the radiators, the enclosure C is nailed into position and valve 26 and trap 27 are connected to the 75

headers of the heating element with the valve on the end nearest the steam supply stub-up A and the trap on the other end. The pitch or setting of each radiator is established generally by means of physical dimensions, the trap being approximately one-half inch less in height than the valve, and accurate adjustment is then made by means of the feet 53 on the trap and 77 on the valve.

10 To complete the piping connections, the steam fitter measures the distance from the stub pieces A and B to the ball-joint union connections 48 and 72a and cuts pipe nipples 74 to suit.

The valve stem 63 is jointed to provide means for installing the radiator structure in the arched inlet opening 23 of the base-board 22 and the handle or knob 67 is removably connected to the end of the stem in order to provide for the extension of said stem through the grille 21 when such closure is used.

It will be readily seen that with the type of trap and valve disclosed herein, the means for supporting the radiator or heating element is entirely divorced from the enclosure. This simplifies the entire construction and makes all enclosures interchangeable for hand, whereas enclosures must be constructed especially for hand if support is part of the enclosure. In the latter case, building construction is quite often delayed because fabrication of enclosures cannot be started until hand of each radiator is determined from the piping arrangement.

In the valve and trap shown, the ball-joint unions are employed to permit grading of the radiator or heating element and pipe laterals with valve and trap in plumb position. This gives added flexibility to installation as the steam fitter can install piping plumb, whereas if ordinary unions were employed the piping would have to be installed at an angle in order to make up the joint at the connections to the valve and the trap. It will be obvious that this angle varies for each length of radiator involved.

Of course, the radiator structure comprising the heating element with the novel valve and trap as illustrated and described herein may be varied in many ways without departing from the invention herein set forth and hereafter claimed.

The invention is hereby claimed as follows:

50 1. In a radiator structure, an enclosure of substantially cuboid shape provided with an air inlet extending transversely across the lower portion thereof and an air outlet extending transversely across the upper portion thereof, a heat radiating unit mounted within said enclosure inwardly of said air inlet and accessible therethrough, said heat radiating unit comprising a pair of tubular headers with interconnecting finned tubes, said tubular headers having piping connections at right angles to said tubes, a steam supply valve and a thermostatic trap having inlets and outlets at substantially right angles, said inlets and outlets being provided with universal pipe connecting means having ball jointed unions each comprising a flanged nipple, a ball member and a flanged nut for securing the nipple member to the ball member, and being so constructed that the cooperating flange faces of the nipple and nut contact annularly regardless of alignment of the 65 nipple and ball member, said steam supply valve and thermostatic trap having their outlet and inlet respectively communicating directly with said piping connections in said tubular headers, and means on said steam supply valve and thermostatic trap to support and grade said heat ra-

diating unit, said steam supply valve inlet and said thermostatic trap outlet providing for connection to the supply and return piping respectively of a heating system.

2. In a radiator structure, an enclosure of substantially cuboid shape provided with an air inlet extending transversely across the lower portion thereof and an air outlet extending transversely across the upper portion thereof, a heat radiating unit mounted within said enclosure inwardly of said air inlet and accessible therethrough, said heat radiating unit comprising a pair of tubular headers with interconnecting finned tubes, said tubular headers having piping connections at right angles to said tubes, a steam supply valve and a thermostatic trap having inlets and outlets at substantially right angles, said inlets and outlets being provided with universal pipe connecting means having ball jointed unions each comprising, a ball-shaped body portion, a nipple provided with socket means, a nut for holding said socket against said ball-shaped body portion, said nut and socket being so constructed and arranged that with angular setting of said nipple with respect to said ball-shaped body portion an annular contact between the cooperating members is maintained, said steam supply valve and thermostatic trap having their outlet and inlet respectively communicating directly with said piping connections in said tubular headers, and means on said steam supply valve and thermostatic trap to support and grade said heat radiating unit, said steam supply valve inlet and said thermostatic trap outlet providing for connection to the supply and return piping respectively of a heating system.

3. In a radiator structure having a pair of headers with interconnecting tubes, said headers having piping connections at right angles to said tubes, a steam supply valve and a thermostatic trap having therein inlets and outlets at substantially right angles, said valve and trap having their outlet and inlet respectively directly connecting said piping connections in said headers, and ball jointed unions on said trap and valve providing flexibility of connection to the piping of a heating system, said unions each comprising, a ball-shaped body portion, a nipple provided with socket means, a nut for holding said socket against said ball-shaped body portion, said nut and socket being so constructed and arranged that with angular setting of said nipple with respect to said ball-shaped body portion annular contact between the cooperating members is maintained.

4. In a radiator structure having a pair of headers with interconnecting tubes, said headers having piping connections at right angles to said tubes, a steam supply valve and a thermostatic trap having therein inlets and outlets at substantially right angles, said valve and trap having their outlet and inlet respectively directly connecting said piping connections in said headers, and ball jointed unions on said trap and valve providing flexibility of connection to the piping of a heating system, each ball jointed union comprising a flanged nipple, a ball member and a flanged nut for securing the nipple member to the ball member, and being so constructed that the cooperating flange faces of the nipple and nut contact annularly regardless of alignment of the nipple and ball member.

5. In a radiator structure having a pair of headers with interconnecting tubes, said headers having piping connections at right angles to said

- tubes, a steam supply valve and a thermostatic trap having therein inlets and outlets at substantially right angles, said valve and trap having their outlet and inlet respectively directly connecting said piping connections in said headers, ball jointed unions on said trap and valve providing flexibility of connection to the piping of a heating system, each ball jointed union comprising a flanged nipple, a ball member and a flanged nut for securing the nipple member to the ball member, and being so constructed that the cooperating flange faces of the nipple and nut contact annularly regardless of alignment of the nipple and ball member, and separate means on said valve and trap for adjusting the pitch of said tubes.

6. In a radiator structure having a pair of headers with interconnecting tubes, said headers having piping connections at right angles to said tubes, a steam supply valve and a thermostatic trap having therein inlets and outlets at substantially right angles, said valve and trap having their outlet and inlet respectively directly connecting said piping connections in said headers, and ball jointed unions adjacent the inlet and outlet connections of both valve and trap for providing flexibility of connection to the piping of a heating system, each ball jointed union comprising a flanged nipple, a ball member and a flanged nut for securing the nipple member to the ball member, and being so constructed that the cooperating flange faces of the nipple and nut contact annularly regardless of alignment of the nipple and ball member.
- 35 7. A thermostatic trap for steam radiators,

comprising an upper and a lower chamber, a port between said chambers, inboard thermostatic means controlling said port, a vertical inlet connection for the radiator leading into the upper chamber, a horizontal outlet connection for a return pipe leading from the other chamber, ball jointed unions adjacent the inlet and outlet connections for providing flexibility of connection, each ball jointed union comprising a flanged nipple, a ball member and a flanged nut for securing the nipple member to the ball member, and being so constructed that the cooperating flange faces of the nipple and nut contact annularly regardless of alignment of the nipple and ball member, and lugs provided with adjustable feet for plumbing and supporting said radiator.

8. A valve for radiators, comprising a casing having a hollow body, a partition dividing the same into two compartments, a port in said partition, a valve controlling said port, means for connection to a radiator, like inlets at right angles to said connecting means, a ball jointed member for selectively connecting one of said inlets and the steam supply pipe, means closing the other inlet, feet on said valve, and means adjustable in said feet for supporting said radiator, said means for connection to the radiator and said ball jointed member each provided with a union comprising a flanged nipple, a ball member and a flanged nut for securing the nipple member to the ball member, and being so constructed that the cooperating flange faces of the nipple and nut contact annularly regardless of alignment of the nipple and ball member.

CLIFFORD J. SCHLAFMAN. 35
